Levin Faust,

B. N. Morrissey, Attn:

UNITED STATES PATENT OFFICE.

LEVIN FAUST, OF ROCKFORD, ILLINOIS, ASSIGNOR TO NATIONAL LOCK COMPANY, OF ROCKFORD, ILLINOIS, A CORPORATION OF ILLINOIS.

LOCK.

SPECIFICATION forming part of Letters Patent No. 779,151, dated January 3, 1905.

Application filed November 28, 1903. Serial No. 183,081.

To all whom it may concern:

Be it known that I, LEVIN FAUST, a citizen of the United States of America, residing at Rockford, in the county of Winnebago and State of Illinois, have invented certain new and useful Improvements in Locks, of which the following is a specification.

My invention relates to the class of locks commonly known in the lock trade as "mortise-locks." Its object is the production of a strong serviceable lock of the simplest and compactest construction possible; and it consists of certain new and useful features of construction and combinations of parts especially devised to those ends, all as hereinafter fully described, and specifically pointed out in the claims.

Referring to the accompanying drawings, which form a part of this specification, Figure 1 is an isometrical detailed view of all the parts of a complete lock embodying my invention with the portions composing its supporting-base separated for the purpose of showing the interior construction and arrangement thereof. Fig. 2 is a central longitudinal section of the same with the two parts of the supporting-base placed and secured together. Fig. 3 is a transverse section of the lock and its key. Figs. 4 and 5 are isometrical detailed views for illustrating the operation of the lock-bolt. Fig. 6 is a like view of the lock-bolt. Fig. 7 is also a like view of a key for operating the same.

Like letters of reference indicate corresponding parts throughout the several views.

The supporting-base of the lock may be composed of two parts A and B, which approximate in form to halves of a hollow cylinder. These parts terminate at one end in integral lugs A' B' for securing them together. A bolt-slideway B² is formed therein, and the end portions A² B³ thereof serve as closures for the supporting-base and also to arrest the travel of the lock-bolt, to be next hereinafter described.

C is a bifurcated slidable bolt mounted in the slideway B² in the supporting-base and having each rearwardly-extending furcation C' and C² thereof transversely offset at C³ C⁴,

respectively, to form a pair of shoulders thereon, one pair, C⁵, for engagement of a key therewith and the other pair, C⁶, for limiting the travel of such bolt C. The employment of the offsets C³ C⁴, extending the full width of the furcations C' C², adapts their bolt C to be engaged and operated by a relatively long key-bit, which will give a long positive throw to such bolt C with little rotary movement of the key-stem, a desirable result not heretofore attained in locks of small transverse diameter.

D is a pin seated in and transversely to the part B of the lock-supporting base.

E is a key provided with a bit E' and adapted by the cleft E² therein to bestride the offset portions C³ C⁴ of the bolt C and engage the shoulders C⁵ on the bifurcation C' thereof and therethrough operate such bolt C. The key E is also provided with a pipe portion E³, adapted to admit and turn upon the pin D.

F is a post passed transversely through the lugs A' B' on the parts A B to secure them firmly together.

The form of the bolt C is such that the inner and adjacent edges of its furcations C' C² frictionally contact the post F and therewith serve in lieu of a spring to control such bolt C.

Figs. 4 and 5 clearly indicate the limits of travel or throw of the bolt C when acted upon by its key E.

What I claim as new, and desire to secure by Letters Patent, is—

1. In a lock, the combination of a supporting-base with a sliding bolt provided with a bifurcated rear extension, one furcation of said extension offset to form a pair of key-engaging shoulders, said shoulders extending the full width of the furcation, substantially as and for the purpose specified.

2. In a lock, in combination, a supporting-base, having a bolt-slideway therein, and a bifurcated bolt mounted in such slideway—having each furcation thereof transversely offset to form a pair of shoulders thereon, one pair for the engagement of a key therewith and the other pair for limiting the travel thereof, substantially as and for the purpose specified.

3. In a lock, in combination, a supporting-base having a bolt-slideway therein, a bifur-

cated bolt—mounted in such slideway—having each furcation thereof transversely offset to form a pair of shoulders thereon, one pair for the engagement of a key therewith and the other pair for limiting the travel thereof, and a key having a cleft bit adapted to bestride the offset portions of the bifurcated bolt and engage the shoulders on one of such bifurcations and therethrough operate said

bolt, substantially as and for the purpose so specified.

In testimony whereof I have signed my name to this specification in the presence of two subscribing witnesses.

LEVIN FAUST.
